UNITED STATES PATENT OFFICE.

FLOYD G. BOVARD, OF MANSFIELD, OHIO, ASSIGNOR TO THE OHIO BRASS COMPANY,
OF MANSFIELD, OHIO, A CORPORATION OF NEW JERSEY.

TROLLEY-WIRE HANGER.

1,250,952.

Specification of Letters Patent.

Patented Dec. 25, 1917.

Application filed July 31, 1916. Serial No. 112,343.

To all whom it may concern:

Be it known that I, FLOYD G. BOVARD, a citizen of the United States, residing at Mansfield, in the county of Richland and State of Ohio, have invented certain new and useful Improvements in Trolley-Wire Hangers, of which the following is a specification.

My invention relates to that class of devices which are known as trolley hangers and intended for suspending trolley wires and more particularly where catenary construction is used.

My invention has for its object the suspending of trolley wires from a messenger cable or other support and the economy and convenience of installation of the device are given particular attention in its construction.

Another object of my device is to be capable of maintaining all of its parts in engagement while being installed or removing from the installed position.

Another object is to produce a hanger which is simple to manufacture and hence can be sold cheaply and can be installed in a minimum amount of time.

To the attainment of these ends and the accomplishment of other new and useful objects as will appear, the invention consists in the novel features of construction, combination and arrangement of the several parts hereinafter more fully described and claimed and shown in the accompanying drawings in which:

Figure 1 shows the front elevation view of one form of my invention as embodying the improvements herein described and shows the hanger in installed position, suspending a trolley wire from a supporting cable.

Fig. 2 is an end elevation view of my invention taken at right angles to Fig. 1.

Fig. 3 shows the hanger in Figs. 1 and 2 in partial section as having its clamping jaws sprung apart ready to install on the supporting cable or to remove from the supporting cable.

Figs. 4 and 5 show front and end elevation views of a modified form of my invention shown in Figs. 1 and 2; it being understood that the upper part of the device is the same as shown in Figs. 1 and 2 and the

operation is the same as in Fig. 3 except with the modification as brought out hereinafter.

I have found in construction work of installing trolley wires that it is a decided advantage to use a hanger for supporting the trolley wires which will have the parts of which the hanger is composed so constructed and arranged that during the operation of installing the trolley wire, the parts of the hanger cannot be separated entirely from each other or at least the device will be one in which it is not necessary to entirely separate the parts. This is of particular advantage when it is considered that much of this work is done on the top of tower wagons or cars in extreme cold weather and when it is necessary for the workmen to wear thick heavy gloves which makes their movements clumsy and hence they will be liable to drop the parts if it is necessary to completely separate them. The same is true in changing hangers on a trolley which is charged with electric currents and it is necessary to handle the parts very cautiously. I have also found that it is very desirable to do this work in as little time as possible thereby cutting down the expense of construction and I have covered this point in my arrangement of parts.

The invention consists of a U shaped suspension member 1 which in its installed position will hang from a suspension cable 2 at the point of bend. Numerals 3 and 4 show the clamping jaws for attachment to the ends of the suspension member 1 and for gripping and holding the trolley wire. The clamping jaw 3 is provided in one face with a recess 6 for seating the head 7 of a clamping bolt and is also provided with an aperture 8 disposed at an angle to the recess 6 and through which the head 7 of the bolt is passed to engage and disengage it with the clamping jaw 3; a turn of the bolt after being passed through the aperture 8 will seat the bolt head 7 in the recess 6.

The clamping jaw 4 is provided with an aperture large enough only to receive the shank 9 of the bolt, the end of which is threaded and supplied with a lock washer 10 and a nut 11. The recess 6, aperture 8 and bolt head 7 can be of various shapes and sizes and still perform the function of my

invention. In Figs. 1, 2 and 3 the lower end of the suspension member 1 is attached to the clamping jaws 3 and 4 by a rivet 12, although other means may be employed giving equally as good results and coming within the scope of my invention. The recess 6 being depressed prevents the head 7 of the clamping bolt from turning when tightening the nut 11. In Figs. 4 and 5 I have shown a modification in that the lower end of the suspending member 1 is brought down and underneath the head 7 of the clamping bolt and underneath the spring lock washer 10, and the lower ends are supplied with apertures corresponding to the head 7 and shank 9 of the bolt. The extreme ends of the suspending member 1 which is attached to the clamping jaw 3 are bent outwardly to form the lugs 13 which prevent the head 7 of the clamping bolt from turning when drawing the clamping jaws into place on the trolley wire.

The operation of installing my invention is as follows: The nut 11 is loosened up sufficiently to allow rotating the bolt one quarter turn which causes the head 7 to register with the aperture 8. The jaws 3 and 4 will now spring apart as shown in Fig. 3. The hanger is now placed on the suspension cable 2 as shown, none of the parts being entirely disengaged. The trolley wire is now lifted up into position between the jaws 3 and 4 which are sprung together by hand upon the trolley wire and the clamping bolt placed in clamping position by passing the head 7 through the aperture 8 and giving the head one quarter turn and drawing the nut 11 up tight.

To remove the hanger after being installed it is only necessary to go through the reverse operations as are required to install my hanger. It is sometimes the practice in overhead construction of electric railways to use two trolley wires, one above the other and parallel to each other and my invention is equally as applicable to supporting two conductors as one, it merely being necessary to adapt the clamping jaws to holding two wires in place of one.

Many variations from the above disclosures will be obvious to one skilled in the art and I do not wish to be limited to the specific construction shown in the drawings and disclosed herein.

I claim:—

1. A suspension device for trolley wires comprising a U shaped suspension member, a clamping jaw attached to each end of the suspension member, a groove on each jaw registering with the groove on the other jaw for engaging a trolley wire, an aperture in each jaw opposite each other and a clamping bolt provided with a head, and tightening means passing through both apertures, the head being adapted to engage one of the

jaws only by angular movement when the jaws are in clamping position on a trolley wire.

2. A suspension device for trolley wires comprising a suspension member, clamping jaws attached to the ends of the suspension member which register with each other to engage the trolley wire, an aperture in each jaw which registers with the aperture on the other jaw for receiving a clamping bolt with head, one aperture permitting the passage of the bolt head and the other aperture preventing the passage of the bolt head therethrough.

3. A suspension device for trolley wires comprising a pair of clamping jaws maintained in co-acting position by a U shaped suspension member and made to grip a trolley wire by means of a clamping bolt with upset end arranged to be engaged with and disengaged from one of the clamping jaws by an angular movement of the clamping bolt.

4. A suspension device for trolley wires comprising a pair of clamping jaws and means passing through the jaws for maintaining the jaws in clamping relation on a trolley wire, the clamping means having an upset end for engaging with or disengaging from one jaw by an angular movement.

5. A suspension device for trolley wires comprising a pair of co-acting clamping jaws provided with apertures, clamping means passing through the apertures for maintaining the jaws in clamping relation on a trolley conductor, the clamping means adapted to be disengaged from one clamping jaw by an angular movement without being disengaged from the other jaw.

6. A suspension device for trolley wires comprising a pair of co-acting clamping jaws provided with apertures, clamping means with upset end passing through the apertures, one aperture having a shape corresponding to that of the upset end of the clamping means and the upset end making engagement with said jaw by an angular movement.

7. A suspension device for trolley wires comprising a suspension member, clamping jaws attached to the ends of the suspension member which register with each other to engage the trolley wire, an aperture in each jaw which registers with the aperture on the other jaw for receiving a clamping bolt with head, one aperture being shaped to permit the passage of the bolt head and the other aperture being shaped to prevent the passage of the bolt head therethrough, and means on one face of the jaw engaging the bolt head to prevent the rotation of the bolt during the operation of installation on the trolley wire.

8. A suspension device for trolley wires comprising a pair of clamping jaws main-

tained in co-acting position by a U shaped suspension member and made to grip a trolley wire by means of a clamping bolt with upset end arranged to be engaged with and 5 disengaged from one of the clamping jaws by an angular movement of the clamping bolt, and means on one face of the jaw engaging with the bolt head to prevent rotation of the bolt while it is being drawn 10 tight.

9. A suspension device for trolley wires consisting of a U shaped suspension member, a pair of clamping jaws attached to the ends of the suspension member, a clamping member 15 for causing the jaws to grip a trolley wire, and means on one jaw for engaging and disengaging the clamping means by an angular movement of the clamping means.

10. A trolley wire clamp comprising a

pair of clamping jaws with apertures, a 20 clamping bolt extending through the apertures, and means on one end of the clamping bolt for engaging with and disengaging from one of the jaws by an angular movement of the clamping bolt.

11. A trolley wire clamp comprising a 25 pair of clamping jaws, clamping means for maintaining the jaws in clamping relation on the trolley wire, and means on one jaw for interlocking with the clamping means when it is given an angular movement.

In testimony whereof I affix my signature in the presence of two witnesses.
